(57) **CLAIM**

The ornamental design for an oil burner assembly, as shown and described.

DESCRIPTION

FIG. 1 is a front perspective view of an oil burner assembly showing our new design;

FIG. 2 is a left perspective view thereof;

FIG. 3 is a rear perspective view thereof;

FIG. 4 is a right perspective view thereof;

FIG. 5 is a rear elevation view thereof;

FIG. 6 is a front elevation view thereof;

FIG. 7 is a left elevation view thereof;

FIG. 8 is a right elevation view thereof;

FIG. 9 is a top plan view thereof; and,

FIG. 10 is a bottom plan view thereof.

The broken lines in the drawings represent environmental subject matter and form no part of the claim.
